INVENTOR.

UNITED STATES PATENT OFFICE.

EDGAR L. LOGEE, OF PROVIDENCE, RHODE ISLAND.

DESIGN FOR A BADGE.

SPECIFICATION forming part of Design No. 34,521, dated May 21, 1901.

Application filed March 28, 1901. Serial No. 53,365. Term of patent 7 years.

To all whom it may concern:

Be it known that I, EDGAR L. LOGEE, a citizen of the United States, residing at Providence, in the county of Providence, in the 5 State of Rhode Island, have invented and produced a new and useful Design for a Badge, of which the following is a specification, reference being had to the accompanying drawings, forming part hereof.

10 Figure 1 is a plan view of said badge. Fig. 2 is a side elevation of the same.

As shown in the drawings, the leading or material feature of my design consists of the representation of a beehive as standing on a 15 platform, which is shown as in perspective and as having feet projecting downward from the two lower corners. The portion representing the front edge of the platform is di-

vided into three panels or sections. Upon the beehive is displayed the figure or semblance of a bee whose wings are outstretched, so that the tips of the wings extend beyond the sides of the hive. The outline of the hive consists of a series of convex curves.

Having described my invention, what I 25 claim as new, and desire to secure by Letters Patent, is—

The design for a badge as herein shown and described.

In testimony whereof I have signed my 30 name to this specification in the presence of two subscribing witnesses.

EDGAR L. LOGEE.
